CLAIM

The ornamental design of a wallpaper display unit, as shown and described.

DESCRIPTION

FIG. 1 is a perspective view showing the front left side, and top of my wallpaper display unit; the right side is a mirror image of the left side; the rear and the bottom are plain and unornamented and are not a part of the claimed design; FIG. 2 is a front view thereof; and, FIG. 3 is a sectional view along line 3—3 of FIG. 2. The broken line showing of displayed material is illustrative purposes only and forms no part of the claimed design.
